[57] **CLAIM**

The ornamental design for an inverted fork with detachable suspension attachments for a fork truck, substantially as shown.

DESCRIPTION

FIG. 1 is a perspective view of the inverted fork with detachable suspension attachments for a fork truck according to the present invention seen from one side in its operating position.

FIG. 2 is a perspective view according to FIG. 1 seen from the opposite direction.

FIG. 3 is a perspective view similar to FIG. 1 but showing the inverted fork with the detachable suspension attachments removed.

FIG. 4 is a perspective view similar to FIG. 2 but showing the inverted fork with the detachable suspension attachments removed.

FIG. 5 is a perspective view of one of the upper suspension attachments of the inverted fork according to FIG. 1 seen from one side. The inverted fork is not shown in this Figure (nor in FIGS. 6-8) merely for purposes of clarity.

FIG. 6 is a perspective view of the suspension attachment according to FIG. 5 seen from the other side.

FIG. 7 is a perspective view of one of the lower suspension attachments of the inverted fork according to FIG. 1 seen from one side, and

FIG. 8 is a perspective view of the suspension attachment according to FIG. 7 seen from the other side.
